FEEDING MECHANISM

Wesley P. Shomaker, Richmond, Va.

Application May 7, 1936, Serial No. 78,298

3 Claims. (Cl. 271—28)

My invention relates to feeding mechanisms for machines into which fabric in sheet form is fed piece by piece so that it may be shaped or impressed. It particularly relates to feeding mechanisms for printing machines, and it has for its special object the feeding of small sheets of paper, or envelopes, to a printing machine or other machine designed to perform some operation on the stock, such as embossing, stamping, printing, folding, etc. In describing my invention I shall do so as feeding envelopes to a printing press.

A successful mechanism of this character must be accurate in its operation, must be easily adjustable for the size of stock to be handled, must be synchronized with the press, and must be safely operable at high speed. These characteristics are possessed by my invention.

In the drawings, Figure I shows the principal features of the feed mechanism in plan. Figure II shows the same in elevation and part section. Figure III shows a horizontal section through one of the principal parts of the feed mechanism.

In Figures I and II a hopper 1 holds a number of envelopes 2, standing on edge. The hopper 1 is inclined, to cause the envelopes to slide upwards toward a drum 3, against which the column of envelopes comes to rest. A cylindrical roller 57, usually of wood, is allowed to roll down the hopper and to bear against the back of the column of envelopes to hold it in shape.

The drum 3 is rotatably mounted on the shaft 4. The shaft itself is stationary. Mounted on and keyed to a sleeve 5 which extends from the drum 3 is a gear 6. When the gear 6 is rotated, the drum 3 is rotated. Another gear 7 mounted on shaft 8 meshes with gear 6. Gear 7 may be loose on shaft 8, and held from movement along the shaft by the collars 9 and 10. The drive shaft 11 carries a fixed gear 12, meshing with the gear 7. On the same drive shaft 11 is fixed the chain sprocket 13, which is driven from another chain sprocket mounted on one of the rotating shafts of the printing press by the chain 14. The second sprocket is not shown, since such a drive is familiar to all who are interested in mechanisms of this class.

The press is timed to make a predetermined number of impressions a minute. The chain drive 14—13 and the gears 12, 6, and 7, are so proportioned and timed that the drum 3 will make a proportionate part of a revolution to each impression made by the press. In this

case I have chosen that the drum 3 shall make one fourth of a revolution to each impression made by the press.

In Figure III is shown a horizontal section of the drum 3, taken on line a—b in Figure II, with the hopper and envelopes added in plan. At each end of the drum 3 are the sprocket-wheels 20 and 21; rotatably adjustable about the same axis as the drum; and when adjusted, clamped by one or more screws to the drum 10 itself.

These sprocket-wheels 20 and 21 carry and drive the sprocket chains or belts 22 and 23. See also Figures I and II. These belts are the conveyors which carry the envelopes to the press; and they are driven by the sprocket-wheels 20 and 21, and are carried at their further end by the idlers 24 and 25, which are rotatably mounted on the shaft 26. These conveyors may be steel belts or chains. I have shown belts for the sake of simplicity in the drawings. Hereinafter I shall refer to them as the conveyors or conveyor belts. On the conveyors are attached cleats, or what are known in the art as "pushers", 27, 28, 29, etc., spaced at regular distances apart. These pushers carry the envelopes forward at regular spaced distances apart to the feed rolls 15 to the printing press. At 16 is a brush or other form of soft spring, supported by a bracket 17, and rod 18. The envelopes are carried against this brush, which pushes them against the pushers 27, and so brings them into proper alignment. The conveyor belts may be driven by any suitable number of sprockets on the wheels 20 and 21. I have shown four sprockets, 30, on each wheel; and each sprocket engages through an aperture 31 in the conveyor against one of the pushers 27, etc.

Referring to Figures II and III, the drum 3 is pierced by four air passages or manifolds 40, 41, 42, and 43. These passages enter the drum 3 on the side; the near side in the drawings. From each of the air passages there branch off air tubes 45, 46, 47, and 48, opening on the peripheral face of the drum 3; the several sets of air tubes being spaced apart an equal distance.

The diameter of the drum 3 is a little greater than that of the sprocket-wheels 20 and 21 to give a sufficient clearance, so that an envelope lying against the drum 3 shall not be fouled by the pushers 27, 28, 29, etc. The diameter of the drum can be made greater if desired to increase the space on the periphery between sets 55

of air tubes; or it may be increased to accommodate a greater number of sets of air-tubes, and therefore a greater number of envelopes per revolution.

- 5 The object of the air tubes is that by creating a suction in them this suction shall, as the drum 3 rotates, take hold of one envelope after another, and lift it from the end of the hopper 1. It is desirable that the envelope be released by 10 the air before it comes into contact with the conveyors 22 and 23; and this I bring about by suitably proportioning the air passages 40, 41, 42, 43, and the duration of the partial vacuum which is set up therein.
- 15 Adjustably fixed on the stationary shaft 4, by means of a set screw 56, is the air-valve cover 50. To this cover is fitted at 51 a vacuum hose connection 52; the hole or port 53 passing through the cover 50. The inner face 54 of the cover 50 is exactly parallel with the face 55 of the near end of the drum 3, in which face the air passages 40, 41, 42, 43 are. The face of the drum 55 and the face of the valve-cover 54 are at a convenient distance apart to admit the sliding valve 60, which is fitted neatly between them. The valve 60 is normally stationary, with the valve-cover 50; and it is held from sideways movement with reference to the cover 50 by the shaft 4 which passes through both, and by a lug 61 attached to the valve and passing through the slot 62 in the valve-cover. The hole 64 in the valve through which the shaft 4 passes is elongated to form a slot, lengthwise of the valve; and the slot 62 is lengthwise of the valve-cover. Consequently the valve can slide lengthwise between the cover and the drum 3 to the limit of these slots. A pawl or latch 65 is arranged to bear against the lug 61, or if preferred in a notch cut in the valve 60, to hold 25 the valve in the position shown in the drawings. A spring 66 is arranged between the lug 61 of the valve and another lug 67 on the cover 50 so that it is in compression when the valve and cover are in the relative positions shown.
- 30 The position shown is the operating position. If the latch 65 is tripped so that the lug 61 and with it the valve 60 is freed, the spring 66, relieved of restraint by the lug 61, will open, and will force the lugs 61 and 67 apart, and in 35 so doing will move the valve lengthwise between valve-cover 50 and drum 3 to the limit allowed by the slots 62 and 64. The object of this movement will be stated later. At present it is to be understood that the relative operating positions 40 of valve 60 and valve-cover 50 are as shown in Figures I, II, and III.
- 45 In and passing through valve 60 is an air passage or port 70, which registers with the air port 53 in the valve-cover 50. These two ports, 53 and 70, are the same radial distance from the center of the shaft 4 as are the air passages 40, 41, 42, and 43 in the drum 3. When the drum 3 is revolved around the shaft 4 each of the passages 40, 41, 42, 43 is brought into registration 55 successively with the ports 70 and 53, in the valve and valve-cover respectively, and therefore with the vacuum pump connection 52. Upon registration of the ports 70 and 53 with the air passage 40, for example, the air pressure in passage 40 is at once reduced. And so in passages 41, 42, or 43, as they successively register with ports 70 and 53. Again for example: when passage 40 registers with ports 70 and 53, and the air pressure is reduced in passage 40, so 60 70 75 also will the air pressure be reduced in branch

air passages 45. And so also successively in branch air passages 46, 47, and 48. And when the air pressure is reduced in these branch air passages there will be a suction at the free ends of the said branch passages. (To avoid confusion of the several air passages shown in the drawings I will hereinafter refer to the openings 53 and 70 as valve-cover port and valve port, respectively; to the air passages 40, 41, 42, 43, as the passages; and to the branch air passages 45, 46, 47, and 48 as the tubes.) In the drawings, in Figure III, ports 53 and 70, passage 40, and tubes 45 are in registration. If the vacuum pump be running there will be a suction at the free ends of tubes 45.

15 Refer to Figure II. The drum 3 is revolving in the direction shown by the curved arrow. Passage 40 in the drum 3 is at the beginning of its contact with port 70 in valve 60. As the drum continues to rotate, the passage 40 and port 70 come into and pass through full registration cutting off as passage 40 finally leaves port 70. While passage 40 and port 70 are in registration there will be suction at the free ends of tubes 45; and there will also be suction from the 20 beginning of contact until the final cut-off. The period of contact is dependent upon the diameter of the port 70 and of the passage 40. As drum 3 revolves, and as port 70 and passage 40 make contact, the suction of air at 45 will seize the 25 first envelope, and will lift it out of the hopper. But when one lifts an envelope or a sheet of paper from a hopper or similar container it is a well known fact that the second envelope or sheet will be inclined to adhere to the first, and 30 so be lifted with it. So may the third be inclined to adhere to the second. This tendency is aggravated by the fact that the atmospheric pressure tends to hold the envelopes together, and to hold them against the face of the drum 40 because of the difference in pressure between the air in the room and the air in the tubes 45. There is also the slight pressure exerted against the envelopes in the hopper by the roller 55 57. This holding together and lifting together 45 has rendered many forms of feed mechanisms useless. A part of my invention is to separate the envelope to be lifted from those behind it; and to prevent the lifting of the second or of the succeeding envelopes from the hopper. I 50 first "break" the even plane of the envelope to be lifted, so that it will not cling to the next one. This I do by holding the envelope back along its central vertical line while I pull the two wings, one on each side of the central line, forward by 55 the air suction at the tubes 45. This may be done in several ways; but I do it very simply and effectively by increasing the diameter of the drum at its center, so forming an upstanding rib 72. As the envelopes press against the drum, 60 the tendency of the increased central diameter of the drum is to push the vertical center of the envelope back from the drum. Then just at the point of lifting the envelope, the differential in the air pressure on the two faces of 65 the envelopes forces the two wings of the envelopes against the drum, so holding the first envelope in a broken line. This can be seen in Figure III. Now the first envelope will be held away from the second envelope on either side of 70 the center; and the tendency to lift the second envelope will be only due to the mechanical friction between the two envelopes at their center. Above the envelopes at this point I arrange on a rod 32 the comb bracket 33. See Figures 75

I and II. The bracket is adjustable on the rod 33. To the bracket 33 is adjustably attached the footpiece 34. Slots are cut in one edge of the foot-piece, forming toes 35. These toes are 5 turned upward a little (see Figure II) and stand slightly clear of the face of the drum. On the foot piece 34 there is held, by screws 36, the comb 37, which is slotted along one side to form the fingers 38, which are bent to pass 10 through the slots between the toes 35 of the foot-piece 34. The tips of the fingers 38 I allow to bear lightly against the face of the drum 3. These fingers offer a slight resistance to the passing of an envelope; and this resistance 15 is somewhat greater than the lifting force acting on the second, or third, or succeeding envelopes; and is therefore sufficient to hold them down. But the greater lifting force given to the drum 3 by the vacuum tubes 45 carries the first envelope past the fingers 38, and delivers it to the 20 grip of a belt 77 which runs on crowned idlers 78 and 79; and which bears down upon the face of the drum 3. I prefer to make the belt of rubber. When in operating position this rubber belt is a little stretched. The crowned idlers 25 78 and 79 are mounted with ball or roller bearings on the shafts 80 and 81; and these shafts are dropped into slots 82 and 83 cut in the side plates 84 and 85. These slots converge as they 30 go downwards towards the level of the drum; so that the elasticity of the stretched rubber belt pulling the shafts 80 and 81 together in the slots 82 and 83, causes the rubber belt to hug the face 35 of the drum 3. As the drum revolves it will drive the belt 77 by friction; and when an envelope comes between the rubber belt and the drum there will be friction enough to cause the belt to travel on its idlers.

The two side plates 84 and 85 extend, on the 40 outside of the conveyors 22 and 23, from the hopper 1 to the end of the conveyors. These plates are adjustably mounted on the rods 86 and 87, along which they may be slid in a horizontal plane to adjust the conveyor to different 45 sizes of envelopes. These plates prevent the envelopes from working off the sides of the conveyor.

Referring again to Figure II: the drum 3 lifts the envelope from the hopper by the air suction 50 at the ends of the tubes 45. The envelope is quickly transferred to the grip of the rubber belt 77; and the vacuum pump is disconnected from tubes 45 by the passing out of contact of port 70 and passage 40. A new high vacuum builds up in ports 53 and 70, ready for contact 55 with the next air passage 41, and for the lifting of the next envelope.

The first envelope being transferred to the 60 grip of the rubber belt 77, it is carried over to and deposited upon the conveyors 22 and 23 at 19, Figure II. As the envelope is fed out from under the rubber belt 77, the pushers 28 rise behind it and carry it forward with the conveyor, as at 39 and 49. It will be understood by those 65 familiar with the art that the envelope when it leaves the grip of the belt 77 is likely to be slewed a little on, that is, not exactly square with, the conveyor. It is then carried forward against the brush 16 which aligns the envelope against the pushers 27. It is then carried onward until it 70 is discharged over the conveyor pulleys into the

grip of the press feed-rolls 15. By these rolls it is fed to the printing mechanisms, which are indicated typically by the cylinder 92, in Figure I.

My feed mechanism is so designed and constructed that it may be attached to automatic machines. Such machines are stopped occasionally from one trouble or another, and while it may be necessary or convenient to allow the drive shafts to continue running. It is then 5 desirable to stop the feed, lest good material be fed into the standing machine and destroyed. To this end the latch 65, Figure II, is mechanically or electrically connected with the operating parts of the press, for instance by a rod 93, 10 so that whenever the machine is stopped or trouble occurs the latch 65 is tripped, the spring 66 forces the valve 60 forward the limit allowed by the slots 62 and 64, and the port 70 is thrown out of registration with port 53 and with 15 passage 40. The vacuum is then lost in the tubes 45, and the drum 3 will no longer lift envelopes from the hopper 1.

The sprocket wheels 20 and 21 are screwed or bolted at the ends of the drum 3 by any suitable 20 adjusting means so that the pushers 27, 28, 29, etc., on the two conveyor belts may be correctly timed with the drum 3 and its tubes.

The hopper 1 is constructed with a cast iron 25 box-like end, from which rails 58 and 59 extend 30 as far back as may be desired.

I claim:

1. In a feed mechanism: a hopper for holding envelopes or the like in series; means for lifting the envelopes from the hopper in series; a comb 35 consisting of spring fingers adjusted to allow the lifting of the first envelope in the series which is held by the lifting means but to hold back in the hopper envelopes behind the first envelope; and means for adjusting the resistance 40 of the spring fingers.

2. In a feed mechanism: a hopper for holding envelopes or the like in series; a rotatable cylindrical drum the face of which is in contact with the face of the series of envelopes, and having 45 about its periphery an annular projecting rib adapted to press upon the face of the series of envelopes, and provided with suction means on either side of its rib to hold the first envelope in the series and to lift it from the hopper; and 50 means for rotating the drum.

3. In a feed mechanism: a hopper for holding envelopes or the like in series; a rotatable cylindrical drum the face of which is in contact with the face of the series of envelopes, and having 55 about its periphery an annular projecting rib adapted to press back the center portion of the first envelope in the series, and provided on its face on either side of the rib with suction means to seize the first envelope in the series and to 60 lift it from the hopper; means for rotating the drum; means for creating a partial vacuum in the suction means of the drum during part of a revolution of the drum; means for carrying the envelope forward after its release from the suction means, the said carrying means being provided with means for equally spacing the envelopes apart as it receives them from the drum; and means for aligning the envelopes with the 65 spacing means.

70

WESLEY P. SHOMAKER.
